(57) **CLAIM**

The ornamental design for a trailer hitch set, as shown and described.

DESCRIPTION

FIG. 1 is a perspective view of the main body of the trailer hitch set, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and

FIG. 8 is a bottom plan view thereof.

FIG. 9 is a perspective view of a first hitch, shown separately for clarity of disclosure;

FIG. 10 is another perspective view thereof;

FIG. 11 is a front view thereof;

FIG. 12 is a rear view thereof;

FIG. 13 is a left side view thereof;

FIG. 14 is a right side view thereof;

FIG. 15 is a top plan view thereof, and

FIG. 16 is a bottom plan view thereof.

FIG. 17 is a perspective view of a second hitch, shown separately for clarity of disclosure;

FIG. 18 is another perspective view thereof;

FIG. 19 is a front view thereof;

FIG. 20 is a rear view thereof;

FIG. 21 is a left side view thereof;

FIG. 22 is a right side view thereof;

FIG. 23 is a top plan view thereof; and

FIG. 24 is a bottom plan view thereof.

FIG. 25 is a perspective view of a third hitch, shown separately for clarity of disclosure;

FIG. 26 is another perspective view thereof;

FIG. 27 is a front view thereof;

FIG. 28 is a rear view thereof;

FIG. 29 is a left side view thereof;

FIG. 30 is a right side view thereof;

FIG. 31 is a top plan view thereof; and

FIG. 32 is a bottom plan view thereof.

FIG. 33 is a perspective view of the trailer hitch set in a detached status;

FIG. 34 is a perspective view in a combined configuration of the main body of the trailer hitch set and the first hitch;

FIG. 35 is an another perspective view in a combined configuration of the main body of the trailer hitch set and the second hitch; and,

FIG. 36 is yet another perspective view in a combined configuration of the main body of the trailer hitch set and the third hitch.

(Continued)

The broken lines illustrate portions of the trailer hitch set that form no part of the claimed design.
